UNITED STATES PATENT OFFICE.

ELLSWORTH A. HAWTHORNE, OF BRIDGEPORT, CONNECTICUT.

DESIGN FOR A LAMP.

43,144.

Specification for Design.

Patented Oct. 15, 1912.

Application filed August 1, 1912. Serial No. 712,790. Term of patent 7 years.

To all whom it may concern:

Be it known that I, ELLSWORTH A. HAWTHORNE, a citizen of the United States, and a resident of Bridgeport, county of Fairfield, State of Connecticut, (whose post-office address is 35 Spruce street, Bridgeport, Connecticut,) have invented a new and original Design for Lamps, of which the following description, in connection with the accompanying drawing, is a specification.

In the drawing, Figure 1 shows a side elevation of a lamp having the design of

my invention, and Fig. 2 shows a front elevation of the same.

What I claim is—

The ornamental design for a lamp, as shown.

In testimony whereof, I have signed my name to this specification, in the presence of two subscribing witnesses.

ELLSWORTH A. HAWTHORNE.
